MOLDED FIBER MATERIAL-HANDLING PALLET

Watson S. Eastman, 4303 SW. Hillside Drive,
Portland, Oreg. 97221

Filed July 8, 1969, Ser. No. 18,109

Term of patent 14 years

Int. Cl. D12—99

U.S. Cl. D14—3

Fig. 1.

Fig. 2.

FIG. 1 is a top plan view of a molded fiber material handling pallet showing my new design;

FIG. 2 is a bottom plan view;

FIGS. 3 and 5 are views in side and end elevation respectively;

FIGS. 4 and 6 are transverse sectional views taken along lines 4-4 and 6-6 of FIG. 1 respectively; and

FIG. 7 is a transverse sectional view taken along line 7-7 of FIG. 3.

I claim:

The ornamental design for a molded fiber material-handling pallet, as shown.
